UNITED STATES PATENT OFFICE

2,429,810

MULTIPLE CONNECTOR

David Gottlieb and Anthony V. Jerard,
Chicago, Ill.

Application May 18, 1946, Serial No. 670,678

4 Claims. (Cl. 173—328)

1

This invention relates to certain new and useful improvements in multiple connectors. More particularly the invention relates to a jack and a plug construction and has for its principal object the provision of an improved construction of this character which will be highly efficient in use and economical in manufacture.

Among the several objects of the invention is the provision of a jack comprising a plurality of separate and spaced sockets each having the provision of a resilient tongue or extension for retaining the prongs of a plug within the socket, with the plug and socket having effective and positive electrical contact with each other.

A still further and equally important object of the invention is the provision of a jack having one or more sockets each formed from a blank, with portions of the blank providing an extension for the connection, by means of solder or the like, of a conductor wire or wires thereto and a wall adjacent the extension to prevent admission of the solder or connecting material into the socket.

Yet another and equally important object of the invention resides in the provision of a simple arrangement for mounting the sockets of the jack upon the mounting plates of the jack.

Another object of the invention is the provision of a multiple connector having parts related with respect to each other in a manner affording expeditious assembly of the jack of the multiple connector, and in which the jack comprises the minimum number of parts, thereby to afford economical manufacture.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a plug and jack embodying the invention;

Fig. 2 is a fragmentary side elevational view of the same;

Fig. 3 is a typical end view of the same;

Fig. 4 is a plan view of the jack illustrated in Fig. 1;

Fig. 5 is a cross sectional detail view taken substantially on line 5—5 of Fig. 6;

Fig. 6 is a fragmentary side elevational view of one of the sockets of the jack;

Fig. 7 is a side elevational view similar to that of Fig. 6 showing the reverse side thereof;

2

Fig. 8 is a plan view of one of the sockets removed from its mounting plate.

The drawings illustrate the preferred form of construction by which the several objects of our invention are accomplished.

Most jacks of a multiple connector with which we are familiar, prior to the advent of our invention, include a plurality of sockets each having an indented side wall or each provided with a longitudinal slit to provide on opposite sides of the slit resilient walls for yieldably gripping the prongs of a plug. In either case we have found from actual practice that by the projection of the prong into the socket and its frequent removal and replacement therein, there results the destruction of the resiliency of the indented wall or the longitudinally slit wall, with the result that there is a loose connection between the socket and the prong. In other words, the frequent insertion of the plug in the socket expands the socket out of its normal position, with the resulting loose connection.

As heretofore indicated, it is one of the objects of the invention to provide a plug, the sockets of which are so constructed as will assure a positive contact between the sockets and the prongs regardless of the frequent removal and replacement of the prongs. To accomplish this and other objects of the invention, we provide a jack generally indicated at 10, which comprises a separating plate 11 of elongated formation and of insulating material. Extending in side abutment with this intermediate plate 11 are mounting plates 12 and 13 likewise formed of insulating material. Between the end portions 14 of the plates 12 and 13 and the end portions 15 of the plate 11 are positioned spacer blocks 16. These blocks 16 are provided with angularly formed feet 17 perforated as at 18 to permit passage of a connecting element, such as a screw or the like, for connecting the jack 10 to a fixed support. These spacer blocks 16 and the plates 11, 12 and 13, are secured together by means of connecting elements 19 in the form of nut and bolt members.

The mounting plates 12 and 13 are each provided with slots 21 at opposite longitudinal edge portions 20.

The sockets 22 of the jack are each formed from a blank of conductive material, formed to provide opposite side walls 23 and a medial wall 24, with the medial wall 24 having an extended portion 25 to provide an inclined bottom 26 for the socket 22, and beyond this bottom 26, the extension provides a lip or finger 27, perforated at

28, and to which is adapted to be connected by solder or the like a conductor wire (not shown).

Extending from the side walls 23 are extensions 29, terminating into angularly disposed attachment lugs 30. These extensions 29 are spaced from each other as best shown in Fig. 5 and are adapted to snugly pass into the slots 21, with the attachment lugs 30 disposed between the mounting plate and the intermediate plate 11.

By this method of mounting the sockets upon their respective mounting plates, the slots 21 and extensions 29 cooperate to properly locate the sockets in the same horizontal plane and firmly position the sockets upon their respective mounting plates. In assembling the sockets on their respective mounting plates, it is customary for the operator to form the angularly disposed attaching lugs 30 after the extensions 29 have been positioned in their respective slots 21.

Each of the sockets 22 has struck from the front wall 24 and inwardly and downwardly, a resilient finger 31. The length and shape of this finger 31 may vary according to the size of the socket and the prong to be engaged therein. With respect to size, it is pointed out that the drawings accompanying this application illustrate the device as being drawn on a two-to-one scale. This is done for the purpose of better illustrating the invention and is not to be intended as a limitation to size.

Any number of sockets may be provided and the plug 32 to be associated therewith may comprise any number of prongs 33. This plug 32 comprises a mounting plate 34 from which the prongs 33 extend in pairs so as to engage the sockets on opposite sides of the jack.

The frequent insertion and withdrawal of the prongs in the sockets will in no way effect the normal projected position of the yieldable fingers 31, and by virtue of the projection of these fingers 31 into the sockets there will always be maintained a positive contact between the sockets and the prongs of the plug. As the fingers project inwardly and downwardly, it is obvious that little exertion is necessary for the insertion of the prongs in the sockets; that the withdrawal of the prongs from the sockets is in a direction away from the fingers 31; and it will be apparent that there will always be a contact between the prongs and the sockets until the prongs completely disengage the fingers 31. Therefore, by reason thereof, an inadvertent partial insertion of the prongs in the sockets will, unlike multiple connectors with which we are familiar prior to our invention, nevertheless result in a positive and effective contact between the sockets and the prongs.

The extended portion 25 providing the bottom wall 26 for the sockets, prevents the admission of solder into the sockets during the connection of the conductor wires with the lips 27. This is of particular advantage because should the operator making the connection between the connector wire and the lips 27 do so with the sockets turned upside down, the absence of this bottom wall would allow the molded solder to run into the socket and thereby interfere with the function of the fingers 31 and the insertion of the prong in the socket.

As our multiple connector comprises few parts which are simple in construction, it is manifest that assembly is greatly facilitated and the cost thereof reduced to a minimum.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having thus described our invention, what we claim as new and desire to protect by Letters Patent is:

1. A socket for a jack of a multiple connector comprising a body providing side walls and an intermediate front wall, with the front wall pierced to provide an inwardly and downwardly extending yieldable finger, the side walls having extending from the free edges thereof angularly disposed attachment lugs adapted for attachment to a mounting plate, and the front wall providing an extension having an intermediate portion providing a bottom wall for the socket, and an upper portion providing a perforated lip adapted for connection to a conductor wire.

2. A socket for a jack of a multiple connector comprising a body providing side walls and an intermediate front wall, with the front wall pierced to provide an inwardly and downwardly extending yieldable finger, the side walls having extending from the free edges thereof angularly disposed attachment lugs adapted for attachment to a mounting plate, and the front wall providing an extension having an intermediate portion providing a bottom wall for the socket.

3. A socket for a jack of a multiple connector comprising a body having means for attachment to a mounting plate, and a front wall pierced to provide an inwardly and downwardly extending yieldable finger, the front wall having an extension providing a medial portion providing a bottom wall for the socket and an outer portion providing a lip for connection to an electrical conductor.

4. A socket for a multiple jack formed from a single piece of material bent to provide side walls and a front wall, mounting lugs extending from the free edges of the side walls, the front wall having an extension providing a bottom wall for the socket and a lip, the latter adapted for connection with an electric conductor.
